CONTAINER LABEL

Roy E. Hanson, Wauwatosa, Wis., assignor to
 Milprint Products Corporation, Milwaukee,
 Wis., a corporation of Delaware

Application October 1, 1934, Serial No. 746,335

3 Claims. (Cl. 40—2)

The present invention relates in general to improvements in the art of marking commodities as for identification purposes or otherwise, and relates more specifically to improvements in the 5 production of labels and packages especially adapted for cooperation with segregated batches of various kinds of merchandise.

It has heretofore been common practice in the art of merchandising canned commodities to provide the metal containers with opaque and highly decorated external labels, in an endeavor to augment the attractiveness of the packages and to thereby promote the sales of the merchandise. These prior labels, being non-transparent, 15 naturally concealed the major portion of the shiny and light reflective surfaces of the tin cans to which the labels were applied, and relied solely upon the decoration applied to the normally exposed surfaces of the labels themselves, to produce the desired decorative appearance. It is a well established fact that the visible attractiveness of the package in which commercial products are confined has a great deal to do with the salability of the merchandise, and in the case of 20 canned goods, past efforts in enhancing the attractive appearance have been confined mainly to the pleasing configurations of the receptacles or to the decorations applied to the opaque labels which are in general use at the present time.

The present invention has for an object the production of an improved label especially applicable to a shiny surfaced, rigid container, whereby the attractive appearance of the final package is enhanced by a cooperative coaction 25 of the label with the light reflective surface of the receptacle.

Another object of the present invention is to provide a container label having a normal, relatively unattractive finish before application 30 thereof to the receptacle, but which will present a satiny and emblazoned appearance when applied to the final package.

A further object of the invention is to provide a transparent or translucent label having 35 decorative or printed matter applied thereto either locally or thru-out its entire area, with the aid of transparent or translucent coloring matter, so that when the label is applied to a container, the latter will provide a background for 40 enhancing the aesthetic appearance of the label.

Still another object of the invention is to provide an improved combination comprising a container having a rigid wall provided with a light reflective surface, and a transparent or translucent label having a decorated or colored area co- 45

operating with the light reflective surface of the container to create a satiny external appearance.

An additional object of the invention is to provide a new and useful label of single thickness and of simple structure, especially applicable to 5 metal, glass, porcelain, or similar rigid containers, preferably of circular shape, so as to enhance the aesthetic appearance of both the label and the container to produce a final package having a sanitary and pleasing appearance. 10

Another object of the invention is to provide a highly effective label which may be produced at moderate cost, and which may also be conveniently applied to a container such as a tin can, a bottle, or a jar. 15

These and other objects of the present invention will be apparent from the following detailed description.

A clear conception of one specific embodiment of the invention and of the mode of fabricating 20 the improved labels and of applying the same to containers may be had by referring to the drawing accompanying and forming a part of this specification, in which like reference characters designate the same or similar parts in the several 25 views.

Fig. 1 is a perspective view of an ordinary tin can having one of the improved labels in flat condition, positioned in front of the container, preparatory to applying the label to the cylindrical, outer surface of the can; and 30

Fig. 2 is a similar perspective view of the finally assembled can and label.

While the invention has been shown and specifically described as being applied to a label 35 formed of translucent glassine paper provided with decorative and printed matter produced with transparent ink, the label being associated with a cylindrical tin can, it is not intended to unnecessarily restrict the scope by such specific 40 embodiment since the new and advantageous results may obviously be secured by varying certain characteristics of both the label and the container to which it is applied.

In the specific embodiment illustrated in the 45 drawing, the container is an ordinary commercial tin can 4 having a cylindrical, rigid wall, the outer surface 5 of which is shiny and light reflective, simulating a mirror. The outer label 6 is formed of a single sheet of translucent glassine 50 paper and is provided with a colored area 7 produced with transparent ink or other coloring material, and also has decorative borders 8 and printed matter 9 thereon. These borders 8 and printed matter 9 may either be uncolored, or 55

produced with transparent or opaque coloring matter, such as ink, applied to the inner or outer face of the glassine sheet. The label 6 is preferably of sufficient length to completely encircle 5 the can wall 5, and one end of the label is provided with an adhesive coating adapted to be attached to the opposite end, which this adhesive is capable of overlying.

In order to apply the improved label 6 to a can 10 4, it is only necessary to wrap the finished label into snug coaction with the shiny outer surface of the wall 5 and to thereafter adhesively unite the overlapping label ends, and this may be done either before or after the container has been supplied 15 with merchandise, but preferably thereafter. If the label 6 is brought into close proximity to the light reflective surface of the can 4, this surface reflects a certain amount of light thru the transparent and translucent label areas 20 and thereby produces a satiny or emblazoned effect upon the eye of an observer and results in the production of pronounced high-lights and contrasting shadows which greatly enhance the aesthetic appearance of the package.

25 By a proper selection of colors and of transparent or translucent areas, it is possible to produce marvelous aesthetic effects, and to even create pronounced perspective effects upon representations of objects such as fruits or vegetables 30 pictorially displayed upon the label in translucent, natural coloring. The emblazoned effect produced by the shiny background afforded by the rigid can wall 5 with which the label 6 snugly coacts, may be varied thru-out a great range, by changing 35 the color and the degree of transparency of the coloring matter with which the designs or printing are applied, and may also be altered by varying the characteristics of the sheet of material from which the original label is produced.

40 For example, "Cellophane" or other regenerated cellulosic material, or tissue paper, may be substituted for the glassine paper specifically shown and described, and the reflective outer surface of the container may be plated a bronze or a gold 45 color, or may be left uncolored but shiny, as in the case of glass bottles or porcelain jars.

It is noteworthy that the best results are perhaps obtained by stretching the transparent or translucent label 6 into snug coaction with the light reflective surface of the container 4, and this 50 is more readily accomplished when a rigid, walled container is employed. By utilizing a label having water-proof characteristics, the use of specially treated cans may be eliminated since the label 55 will, to some extent, perform the function of the special treatment. It has been found that cans having ordinary opaque labels applied thereto, when disposed on the shelves of a store and in relatively dimly lighted places, become duller in 60 appearance due to the poor light; but with the

improved labels, such surroundings and relative dim lighting have the effect of increasing the brilliancy of the packages. The actual cost of producing the improved labels is exceedingly moderate due to the simplicity thereof, but the 5 vastly improved aesthetic appearance created by the cooperation of these new labels with the final package has greatly increased the salability of the packages fabricated in accordance with the present invention.

10 It should be understood that it is not desired to limit the present invention to the exact details of production of the labels or to the precise type of containers herein shown and described, for various modifications within the scope of the 15 claims may occur to persons skilled in the art.

It is claimed and desired to secure by Letters Patent:

1. An attractive and ornamental merchandizing package, comprising, a container having a 20 preformed rigid wall provided with a smooth and shiny external light-reflective surface, and a label 25 of highly translucent sheet material having relatively less translucent areas, said label being confined in snug engagement with said wall whereby light rays are reflected outwardly by the shiny surface through the label to produce a satiny appearance at the highly translucent area and to give the visual impression that said less translucent areas are applied directly to the 30 container surface.

2. An attractive and ornamental merchandizing package, comprising, a can having a preformed cylindrical rigid wall provided with a smooth and shiny curved external light-reflective surface, and 35 a tinted label of highly translucent sheet material having relatively opaque characters thereon, said label being confined throughout its area in snug engagement with said wall whereby light rays are reflected outwardly by the shiny surface 40 through the tinted label area to produce a satiny appearance with regular high-lights and contrasting shadows and to give the visual impression that said characters are applied directly to the can surface, the ends of said label being adhesively 45 inter-connected to secure said label in position upon the can.

3. The method of producing illusory effects for display containers which consists in preforming a smooth polished rigid light reflecting metal wall 50 surface and then closely applying to and over said wall surface in intimate smooth and uniform contact therewith, a flexible sheet of translucent material having display material thereon, whereby the contacting light reflecting wall surface and translucent sheet produce the visual 55 effect of the display material on said sheet as being disposed directly upon the polished metal wall surface.
